UNITED STATES PATENT OFFICE.

ELMER C. PFEIL AND OTTO BEMISDERFER, OF HAMMOND, INDIANA, ASSIGNEES TO
CENTRAL RAILWAY SIGNAL COMPANY, OF PITTSBURGH, PENNSYLVANIA, A COR-
PORATION OF NEW JERSEY.

RAILWAY SIGNAL-TORPEDO.

1,171,876.

Specification of Letters Patent. Patented Feb. 15, 1916.

Application filed September 19, 1913. Serial No. 790,703.

To all whom it may concern:

Be it known that we, ELMER C. PFEIL and OTTO BEMISDERFER, citizens of the United States, residing at Hammond, in the county 5 of Lake and State of Indiana, have invented certain new and useful Improvements in Railway Signal-Torpedoes, of which the following is a specification, reference being had therein to the accompanying drawing.

10 Our invention relates to improvements in railway signal torpedoes, and pertains to that class in which the case for the explosive compound is made from a single piece of non-flying material, such as paper, 15 cloth or any other suitable material.

We are aware that it is not new to form a torpedo from a single piece of non-flying material, for this is disclosed in Patent No. 999,113, dated July 25th 1911, to Alfred H. 20 Knapp, and our present improvement pertains to the manner of attaching a spring rail-engaging clip to the form of torpedo disclosed in said patent.

The primary object of our present invention is to provide a simple, effective and cheap manner of attaching a spring clip to a one piece fibrous pliable non-flying torpedo case.

In the accompanying drawing Figure 1 30 is a top perspective view of our improved torpedo. Fig. 2 is a sectional view on the line 2—2 of Fig. 1. Fig. 3 is a plan view of the single piece from which the case is made, the parts shown opened upward. Fig. 4 35 is a perspective view showing the side flaps of the case closed and the spring clip attaching member in position ready to have the end flaps closed thereover.

Referring now to the drawings forming 40 part of this specification, A is the case in which is placed a suitable explosive compound B, preferably in tablet form. Referring now particularly to Fig. 3, the case A is formed of a single piece of pliable non- 45 flying material, which has a central portion 1, and this central portion is depressed in suitable dies to form a pocket or recess 2, for receiving the explosive compound B. The form of torpedo here shown is what 50 is known in the art as a wedge-shaped torpedo, which, as heretofore stated, in commercial practice has been almost exclusively constructed of metal. This form of torpedo has recognized advantages in that it pre-

sents a tapered portion for the wheels of the 55 locomotive to strike; thus avoiding the tendency for the torpedo to fly or "pop" from under the wheel, which has a tendency to occur where an abrupt wall is presented as in other forms of torpedoes. The central 60 portion 1 is provided with the side flaps 3 and with the end flaps 4. In the process of assembling, the explosive compound B is placed in the pocket 2, one of said flaps turned inward thereover and the other side 65 flap turned inward over the first said side flap, and these two flaps are cemented together by a suitable water-proof cement, thus closing the recess or pocket and holding the explosive compound therein. 70

The rail attaching clip 5 is riveted to a suitable plate 6, preferably of metal, and this plate with the clip attached thereto is placed on top of the outer side flap 3 and the end flaps 4 turned inward over the plate. 75 The said flaps are all about the same width as the center or body-portion 1, so as to positively close the pocket 2 and hold the explosive compound therein. The plate 6 is cemented to the outer side flap 3 and the 80 end flaps 4 are cemented to the outside of the plate 6. As clearly illustrated, the end flaps 4 are less than half the length of the 85 torpedo and of a length to fit against the edges of the spring clip 5. The thickness of the material of the end flaps, together with the cement thereunder when the parts are pressed in position, brings the outer surface of the flaps about level with the outside 90 of the spring clip, so that when the torpedo is placed on the railroad rail, it will set level thereon.

One of the primary advantages of this torpedo is that it presents a form of spring 95 clip torpedo which has been recognized for years as having special advantages and at the same time one which is of a non-flying nature to prevent injury to persons, and yet of sufficient strength and stability to permit the spring clip to be opened up and 100 placed on the railroad rail without injury to the torpedo, therefore presenting a torpedo having all the advantages of the well-known metal wedge-shaped torpedo and without the disadvantages thereof, caused by the flying of the metal case when the torpedo is exploded.

Having thus described our invention,

what we claim and desire to secure by Letters Patent is:

1. In a torpedo of the class described, an explosive compound container composed of a single piece of pliable material having a body-portion with a depression to receive an explosive compound, the body-portion having a pair of side flaps and a pair of end flaps, the width of each of one pair of flaps being substantially equal to that of the body-portion, the said flaps folded over the depression and over each other, a plate placed over the said flaps, a rail-engaging member connected to the plate and extending at right angles to the other pair of flaps, the last said pair of flaps closed over the plate and of a length to prevent overlapping the rail-engaging member for the purpose described, the plate and the flaps being cemented together and to the body-portion.
2. In a torpedo of the class described, an explosive compound container composed of a single piece of pliable material having a body-portion provided with a depression adapted to receive an explosive, the body-portion having side flaps and end flaps, the side flaps folded over the depression, a plate

placed over the flaps and a rail-engaging member connected to the plate and extending transverse the body-portion, the end flaps being of a length less than half the length of the body-portion to prevent overlapping the rail-engaging member and folded over the plate, the flaps and plate and body-portion being cemented together. 35

3. In a torpedo of the class described, an explosive compound container composed of a piece of pliable material having a body portion provided with the depression to receive an explosive compound, and flaps carried by the body portion for closing the torpedo, a plate placed over said flaps, a rail-engaging member connected to the plate and a pair of end flaps closed over the plate, and of a length to prevent overlapping the rail- 45 engaging member for the purpose described.

In testimony whereof we hereunto affix our signatures in the presence of two witnesses.

ELMER C. PFEIL
OTTO BEMIS DERFER.
